R. W. BURNETT

TRUCK

Filed Oct. 25. 1924

Inventor: Richard W. Burnett
By George D. Haight His Atty.

UNITED STATES PATENT OFFICE.

RICHARD W. BURNETT, OF CHICAGO, ILLINOIS.

TRUCK.

Application filed October 25, 1924. Serial No. 745,826.

This invention relates to trucks.

An object of the invention is to provide trucks of light and exceptionally strong construction, which are particularly well adapted for use in the transportation of materials between various departments of stores, mills, factories and the like, or in any other situation in which a light, strong truck may be useful.

10 Another object of the invention is to provide a truck of this character made up of a plurality of thin panels of composite construction, each of which includes a plurality of layers of wood and sheet metal secured together, with means for reinforcing and binding such panels together to provide a truck body receptacle which may be equipped with suitable rollers or wheels.

In the use of trucks of this character the same are frequently bodily transported from place to place and during such transportation it is important that the contents of the trucks be secured against accidental or unauthorized removal, and a further purpose 25 of the present invention is to provide a truck of this character including suitable doors made up of composite panels of the character above mentioned, together with suitable journals and journal bearings associated with the doors and the truck body for swingably mounting the doors on the truck.

A further object of the invention is to provide means for mounting the doors in such manner that they will lie flat against the outer side walls of the truck body when in open position, and when moved to position to close the receptacle, engage means provided adjacent the swinging axes of the doors which limit the closing movement and 40 properly support the doors in the desired closed position.

A still further object of the invention is to provide a composite door panel of the character mentioned, in which portions thereof have been cut away to provide extensions at its corners, the sheet metal of course remaining in position to reinforce the extensions, together with half round stiffening strips of suitable material which are disposed along the opposite faces of the edge of the panel and project along the extensions formed on the panel, the end portions of such strips and the extensions providing cylindrical journals adapted to be received 50 in suitable sockets or brackets on the truck

body to pivotally mount the doors for swinging movement.

Other and further objects and advantages of the invention will more fully and clearly appear from the description and claims hereinafter appearing.

Referring to the drawings, Fig. 1 shows a perspective view of a truck of the character contemplated by my invention. Fig. 2 shows an enlarged, fragmentary top plan view of one upper corner of the truck, together with means for pivotally securing the door thereto. Fig. 3 is a partial, sectional view of the invention on the line 3—3 of Fig. 2, showing the door in closed position. Fig. 4 70 is a partial, sectional view of the invention on the line 4—4 of Fig. 3; and Fig. 5 is a partial, sectional view of the invention similar to Fig. 3, showing the door in open position.

In the drawings, a truck of the character contemplated by my invention is indicated generally by the letter A. Such truck comprises a plurality of side panels 10, and end panels 11, each of said panels preferably being of a composite construction made up of a thin wood sheet or core 12, having thin sheets of sheet metal 13 and 14 secured to its opposite sides as best shown in Figs. 3 and 5, the sheet metal being secured to the wood core by means of a process described and claimed in my reissue Patent No. 14,349 dated September 11, 1917, the construction forming in effect sheet metal veneered panels

80 of great strength and durability, well able to withstand the hard usage to which trucks of this character are generally subjected. The panels 10 and 11 are assembled in rectangular formation, and provided with a suitable bottom, upon which is mounted rollers 15. Such bottom is preferably made up of the same material as the panels 10 and 11, preferably of a plurality of thicknesses 85 of such material. Longitudinally extending bottom strips 16, and transverse strips 17 are provided to which the bottom portions of the panels 10 and 11 are secured. Upright strips 18 extend along each corner of the truck body, to which the ends of the panels

90 10 and 11 are secured, such uprights preferably being in the form of angle bars to which the panels are riveted. The upper edges of the end panels 11 are provided with transverse bars 19, which are preferably in 100 the form of rounded covering strips, each 105 110

provided with a groove 20 for the reception of the upper edge of the related panel 11. The covering strips 19 each preferably has an outer sheathing 21 of sheet metal, the inner edges of such metal sheathing being turned into the groove 20 so as to securely hold the same in position, as best shown at 22 in Fig. 4. The end portions of the covering strips 19 are provided with cut-out 10 portions 23 on their inner sides, for a purpose which will presently appear. Each side panel 10 is provided with a reinforcing strip 24 which is secured thereto on the inner side at its upper edge by suitable rivets 25, 15 the strips 24 preferably terminating some little distance from the end walls 11. The top edge of each wall 10 is outwardly bevelled as shown at 26.

Each corner of the truck is provided with 20 a metallic bracket 27, and as all of such brackets, except for their disposition, are similar in construction and attachment, only one of the same is specifically described herein. Each bracket 27 is angular in form, 25 and preferably U or channel shaped in cross section, the angular portion 28 of such bracket being arranged to fit snugly over the covering strip 19 and sheathing 21, such covering strip being secured to the panel 30 11, and the bracket to the panel 11 and the covering strip, by means of rivets 29 extending through all of the parts.

The angular portion 30 of each bracket 27 has its inner wall 31 disposed against the 35 inner surface of the adjacent panel 10, and in the space between the end of the adjacent reinforcing strip 24 and the panel 11. The opposite wall 32 of the angular portion 30 of the bracket 27 is outwardly spaced from 40 the panel 10, as clearly shown in Figs. 3 and 5, and in conjunction with the bevelled portion 26 of the edge of the panel 10, and the cut-out portion 23 of the covering strip 19, provides a journal bearing 33, defined 45 by the U portion of the bracket, the cut-out portion 23 of the covering strip 19, and the curved bevelled edge 26 of the adjacent side wall 10. Similar bearings 33 are provided by each of the other brackets 27 at the 50 respective corners of the truck body portion, such bearings being adapted for the reception of suitable journals 34, formed on the door members 35, which will now be described.

55 Each of the door members 35 comprises a composite panel made up of layers of sheet metal, and fillers of suitable material, preferably wood, in the same manner as the panels 10 and 11, and the journals 34 are 60 provided by a novel arrangement of the parts. In forming such journals upon the door members 35, stiffening strips 36 are disposed on opposite sides of the edge of the door, such strips being preferably half 65 round in cross section, and secured to the

panel by means of rivets 37, the body portion of the door being cut out as shown at 38, providing projections on the door along which extend the end portions of the stiffening strips 36, the end portions of such strips 70 and the projecting body portions of the door, providing cylindrical journals which fit within the journal bearings, provided by the brackets 27, and the associated parts, thus mounting the door for swinging movement 75 upon such journals. It should be particularly observed that the projections on the door in conjunction with the stiffening strips provide exceptionally strong journals, since they are reinforced by the sheet metal forming 80 part of the door panel.

A suitable lock as shown at 40 may be provided to secure the door members 35 in closed position.

By the above described arrangement the 85 doors are mounted for swinging movement, and it should be noted that such doors when in open position depend closely adjacent the outer sides of the side walls as to be in an out of the way position, and when swung 90 to closed position such doors are supported in the proper position by resting upon the reinforcing strips 24. It should also be particularly observed that the journals 95 formed on the door by the projections of the body portion thereof, together with the stiffening strips provide a strong and durable door and journals, in which the stiffening strips brace the door and the journals, and such journal portions are also reinforced by the sheet of metal forming part 100 of the projecting portions of the body of the door.

While I have herein shown and described what I now consider the preferred manner 105 of carrying out the invention, the same is merely illustrative and I contemplate all changes and modifications that come within the scope of the claims appended hereto.

I claim:

1. In a device of the character described, the combination with a body receptacle having side and end walls and a bottom; angular corner brackets, channel shaped in cross section, one angular portion of each of said 115 brackets fitting over the edge portions of opposed walls, and being secured thereto; and a door having journals disposed in the other angular portions of said corner brackets.

2. In a device of the character described, 120 comprising a body receptacle having side and end walls and a bottom portion; cover strips disposed on the top edges of certain of said walls, said strips being provided with cut-out portions adjacent their ends; angular corner reinforcing members, channel shaped in cross section, each having one 125 angular portion thereof fitting over the adjacent cover strip and being secured thereto; and a door associated with said receptacle 130

- cle having projections journaled in the other angular portions of said corner members, and in the cut out portions of said cover strips.
- 5 3. In a device of the character described, the combination with means providing an opening; of a door for closing said opening, said door being in the form of a composite panel comprising layers of fibrous material and sheet metal, said door being provided with projecting integral portions; and stiffening strips secured to opposite sides of said door, and extending along said projecting portions to provide journals; 10 and means associated with the means providing said opening for the pivotal reception of said journals.
- 15 4. In a device of the character described, the combination with means providing an opening; of a door for closing said opening, said door comprising layers of fibrous material and sheet metal secured together to provide a composite panel, said panel being formed with projecting portions adjacent one edge; and substantially half round stiffening strips secured to the opposite sides of said door and extending along said projecting portions, and in conjunction therewith providing cylindrical journals; and 20 means associated with the means providing said opening for the pivotal reception of said journals.
- 25 5. As an article of manufacture, a composite door comprising a plurality of layers of fibrous material and sheet metal, such door having integral extensions adjacent its edges, and stiffening strips secured on opposite sides of said door and extending along said extensions to provide journals.
- 30 40 6. In a device of the character described, the combination with a body receptacle having side and end walls and a body portion; cover strips secured to the top edges of certain of said walls of said receptacle; reinforcing strips mounted on the inner sides of the other walls of said body portion adjacent the inner top edges thereof; angular corner brackets channel shaped in cross section, one angular portion of each of said 45 brackets being secured to the related cover strip, and the other angular portion of said bracket extending beyond the adjacent wall of the body receptacle; and a door having journals thereon retained in the last named 50 angular portions of said brackets, and bearing against the top edge of the adjacent wall, said doors being supported on the reinforcing strips on the side walls when in closed position.
- 55 7. In a device of the character described, comprising a receptacle including end walls, side walls and a bottom portion, the walls and bottom portion of each including a composite panel made up of layers of fibrous material and sheet metal secured together; 60 cover strips secured to the top edges of the end walls of said receptacle; reinforcing strips disposed on the inner side of the side walls of said receptacle adjacent the top edges thereof; angular brackets channel shaped in cross section, and having one angular portion thereof fitting over the related cover strip; and a door having journals pivotally mounted in the other angular portions of said brackets. 65
- 70 75 8. In a device of the character described, comprising a receptacle including end walls, side walls and a bottom portion, the walls and bottom portion each comprising a composite panel made up of layers of fibrous material and sheet metal; cover strips secured to the top edges of the end walls of said receptacle; reinforcing strips secured on the inner sides of the side walls of said receptacle adjacent the top edges thereof; 70 angular brackets channel shaped in cross section, and having one angular portion thereof fitting over the adjacent cover strip; and a door having journals pivotally mounted in the other angular portions of said brackets, said door being in the form of a composite panel made up of layers of fibrous material and sheet metal secured together. 80
- 85 90 9. In a device of the character described, comprising a body receptacle including end and side walls and a bottom portion; cover strips on the top edges of said end walls; angular corner brackets channel shaped in cross section, each having one angular portion fitting over the related cover strip; and a door having members journaled in the other angular portions of said brackets, said door being cut away to clear said brackets in closed position, and said brackets being 95 cut away to permit swinging of said doors to positions adjacent the side walls of said receptacle. 100
- 100 105 In witness that I claim the foregoing I have hereunto subscribed my name this 22nd day of October 1924.
- RICHARD W. BURNETT.
